A. H. MORTON

PICK COUNTER FOR LOOMS

Filed June 28, 1924

Invention,
Albert Hayes Morton
by his attorney
Katherine Fish Hildreth Henry

UNITED STATES PATENT OFFICE.

ALBERT HAYES MORTON, OF LOWELL, MASSACHUSETTS.

PICK COUNTER FOR LOOMS.

Application filed June 28, 1924. Serial No. 722,950.

To all whom it may concern:

Be it known that I, ALBERT HAYES MORTON, a citizen of the United States, residing at Lowell, in the county of Middlesex and State of Massachusetts, have invented certain new and useful Improvements in Pick Counters for Looms; and I do hereby declare the following to be a full, clear, and exact description of the invention, such as will enable others skilled in the art to which it appertains to make and use the same.

The present invention relates to an improvement in pick counters for looms. In the pick counter illustrated in my Patent No. 1,478,903, dated December 25, 1923, the counting mechanism was supported on a bracket consisting of a strip of flexible metal fastened at one end to the arch of the loom frame, and at the other end to the counting mechanism. This bracket was twisted between its ends so that lateral vibrations were taken care of by the flat in one plane while the longitudinal vibrations were taken care of by the flat in the other plane. This pick counter has been satisfactory in operation and large numbers of pick counters, embodying this invention, have been put in use. The present invention is an improvement on the construction of the counter of the patent. In it provision is made for absorption of vibrations both longitudinally and laterally and a more compact and efficient construction has been produced. The invention consists in a pick counter hereinafter described and particularly defined in the claims. In the accompanying drawings, illustrating the invention, Fig. 1 is a front elevation of a part of a loom showing one form of the invention in position thereon; Figs. 2 and 3 are similar views, omitting loom parts, of second and third forms of the invention; Fig. 4 is a sectional elevation of the construction illustrated in Fig. 1, and Fig. 5 is a section taken on the line 5—5 Fig. 4; Fig. 6 is a sectional elevation of the second form of the invention, and Fig. 7 is a section taken on the line 7—7 Fig. 6; Fig. 8 is an enlarged elevation of the third form of the invention, and Fig. 9 is a sec-

tional elevation taken on the line 9—9 Fig. 8.

The first form of the invention illustrated in Figs. 1, 4 and 5 is described as follows. The counter proper 10 is connected by the flexible drive shaft 11 with the reducing mechanism 12 which is mounted upon the crank shaft 13 of the loom. To the arch 14 on the loom is attached the counter support rod 15. This counter support consists of a rod received in a hole in the flange 16 of the arch 14 and secured thereto by means of nuts 17 which are screwed up against lock washers 18 on opposite sides of the flange 16 of the arch. This provides a firm attachment of the counter support to the loom frame. The counter 10 has a casting 19 upon the top of which is a cylindrical boss 20. The boss is provided with a longitudinal hole 21 reduced in size at 22 to slidingly receive the support rod 15. The hole 21 is closed by the collar 23 which is forced into the open end of the hole with a drive fit. The support 15 is provided with a transverse pin 24 the lower end of which projects into the groove 25 in the boss 20. On each side of the pin 24 are springs 26 of such length that they are under compression when they are assembled. The parts are put together by inserting the rod in the hole in the boss in the counter casting with the two springs in position on it, then the collar 23 is forced into the open end of the hole 21 thereby securing the parts in place. The springs 26 being under compression balance each other and hold the counter in position on the rod with the springs in equilibrium. Longitudinal vibrations of the loom frame are transmitted, of course, to the support 15 but that support may move longitudinally in the counter boss and while some movements of the counter may occur the heavy jars and vibrations of the loom frame are not transmitted to the counter except through the springs 26 which yield in operation owing to the inertia of rest of the counter. The slot 25, which receives the pin 24 is wider than the pin as a result of which the frame of the loom may vibrate forwardly.

and backwardly without imparting other than slight movements to the counter, the capacity of the counter to turn upon the rod permitting it to occupy a position of balance on the rod from which it hangs. The longitudinal vibrations of the loom are more serious than the forward and backward vibrations of the loom and the counter is cushioned against the transmission to it of the longitudinal vibrations by means of the springs. The lateral or forward and back vibrations of the loom are less severe and their direct transmission to the counter is avoided by the construction by which the counter is permitted to turn upon its support. In setting up the counter, the pin 24 of the support rod 15 should occupy the center of the slot 25 in the boss on the counter casing so that the counter may be permitted to have free oscillatory movement about the support within the limits permitted by the difference between the width of the slot and the thickness of the pin. The center of gravity is below the position of the support 15 as a result of which the center of gravity of the counter may remain substantially stationary even with considerable oscillations due to the forward and backward movements of the loom frame.

In the second form of the invention the counter 30 is supported on the support rod 31 in a manner somewhat similar to that of the first form of the invention above described but with these differences; instead of receiving the support 31 in a boss on the top of the counter casing the support is received in a sleeve 32 carried by the casing side 33. This sleeve 32 forms a support for one set of counting wheels 34. The ends of the sleeve 32 project beyond the casing sides 33 and are embraced by collars 35, these collars fitting over the ends of the sleeve 32 with a drive fit. Each collar is provided with a notch 36 to receive a spring end 37. The support rod 31 fits loosely in the center openings in the collars. Springs 38 embrace the support rod 31 and their outer ends 37 project into the notches and collars as above described. The inner ends of the springs 38 are received in notches 39 in the enlargement 40 of the support rod 31. This second form of the invention is assembled as follows:—With the sleeve 32 in position in the counter and the outside collar 35 in place the support rod 31, carrying its springs 38, is inserted through the left hand end of the sleeve 32. The end 37 of the right hand spring is inserted in the hole 36 in the right hand collar 35. The other collar 35 is slipped over the end 37 of the left hand spring 38 and forced with a tight fit on the end of the sleeve 32, the collar and sleeve 32 are thereby rigidly attached to the counter. The springs provide both for

longitudinal movement of the counter on the support rod 31, holding the counter in equilibrium between the pressures of the two springs, and also permit, owing to the torsional resilience of the springs, oscillatory movements of the counter on the rod 31. Upon reference to Fig. 2 it will be seen that the center of gravity of the counter 30 is below the support rod 31 as a result of which forward and backward movements of the loom and consequently such movements of the support 31 tend to oscillate the counter on the pin 31 rather than to cause it to partake of the forward and backward movements of the support 31.

In the third form of the invention the counter 50 is supported on a bracket 51, having a journal 52 which receives the counter support rod 53 secured to the flange 16 of the arch of the loom. The counter 50 is bolted by means of the bolt 54 to boss 55 on the bracket 51, the counter and bracket being carried by the rod 53 and permitted to move longitudinally of the rod and to oscillate thereon. A spring pin 56 is rigidly secured at one end in a hole in the support rod 53. The other end of the spring 56 is loosely received in a hole in the arm 57 which forms a part of the bracket 51. The spring is of steel wire and permits longitudinal vibrations of the loom frame to occur while the counter stands fast. It also permits forward and backward movements of the loom frame while the counter 50 itself stands fast, the spring permitting a limited movement of the loom frame with respect to the counter so as to prevent the transmission of vibrations, both longitudinally and forward and backward, from the loom frame to the counter.

In each of the constructions above described it will be observed that longitudinal vibrations of the loom frame are only transmitted to the counter proper through springs which reduce the severity of the vibrations received by the counter and thereby preserve it from the severe blows, vibrations, or shocks in a longitudinal direction. Similarly, in each case the center of gravity of the counter is offset from the support upon which the counter is carried so that the forward and backward movements of the support will be permitted without being transmitted with force to the counter itself. In each case forward and backward movements or vibrations or blows of the loom frame permit oscillating movements of the counter with respect to its support.

Having thus described the invention, what is claimed is:—

1. A pick counter for looms, comprising a counter proper provided with a part having a bearing, a support for attaching the

counter to the frame of the loom having a portion arranged longitudinally of the loom to be received in the bearing of the counter, and spring means to resiliently resist relative longitudinal movements of the counter and its support.

2. A pick counter for looms, comprising a counter proper and a support for attaching the counter to the frame of the loom,

the counter being pivotally and slidably mounted on the support to have resiliently resisted capacity for movement longitudinally of the loom and a swinging movement in a plane at right angles to such movement.

In testimony whereof I have signed my name to this specification.

ALBERT HAYES MORTON.
